WALL PAPER.

Des.

No. 19,251.

Patented Aug. 6, 188

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 19,251, dated August 6, 1889.

Application filed July 2, 1889. Serial No. 316,342. Term of patent 7 years.

To all whom it may concern:

Be it known that I, CHARLES BOOZE, a citizen of the United States, residing at Buffalo, in the county of Erie and State of New York, have invented a new and original Design for Wall-Paper, of which the following is a specification, reference being had to the accompanying engraving, forming part thereof.

The leading feature of my design consists in groups or bands of raised vermiculate or wavy lines, which produce upon the eye an effect similar to the style of wall decoration which is known as "comb" or "scratch" work. These groups of vermiculate lines are each

composed of a number of equidistant curved lines and are arranged in various directions, so as to cover the surface of the paper, as represented in the accompanying engraving.

The paper is tinted in any desired color.

What I claim is—

The design for wall-paper herein shown and described.

Witness my hand this 21st day of June, 1889.

CHARLES BOOZE.

Witnesses:

JNO. J. BONNER,
F. C. GEYER.
